VACUUM TUBE AND METHOD OF MANUFACTURE

Application filed December 29, 1925, Serial No. 78,124, and in Great Britain December 31, 1924.

This invention relates to vacuum electric tube devices and particularly to the introduction into such devices of vaporizable substances or reagents such as may be employed 5 as getters for the removal of residual gases or more especially for increasing the electron emission from cathodes. In this latter connection alkali metals have been distilled into the tube, the theory being that a molecular 10 layer of the alkali metal is formed upon the surface of the cathode so that the electron emission and efficiency is increased by reason of the fact that these metals have low work functions and consequently permit the 15 cathode to be operated at low temperatures. Caesium is a notable example of a metal of this class. Employing caesium the emission from a tungsten filament at 900° K. is about one-third ampere per sq. cm. of cathode 20 face.

Referring more particularly to caesium this metal is very readily oxidizable so that it cannot be handled and directly introduced into the vacuum electric tube, and the process 25 usually adopted is to heat a mixture of caesium chloride and calcium in an auxiliary glass bulb forming an extension of the main envelope of the tube, thereby producing metallic caesium which is distilled into the 30 main envelope after the latter has been evacuated and is still in connection with the evacuating pump, the auxiliary bulb being subsequently removed. Caesium, however, attacks ordinary lead glass when the temperature 35 is above normal so that it is necessary to effect the reaction in a bulb of special glass such as that known under the registered Trade Mark as Pyrex glass. Furthermore it is necessary that the main tube also consists 40 of a special glass of this nature since it must be sealed to the auxiliary bulb. In any case the heating of the caesium chloride and calcium needs care and skill, and for these reasons vacuum electric tubes of this class have 45 only been rarely employed heretofore.

The object of the present invention is to prevent oxidation of the substance or reagent while it is being inserted into the envelope of the vacuum electric tube device and to vaporize it without directly heating said envelope 50 or any auxiliary portion thereof, so that ordinary glass can be employed. To this end, according to the invention, a decomposable compound of the substance to be vaporized is introduced into the envelope, or a sealed container 55 or capsule containing a quantity of the substance is introduced therein, and, after exhaustion of the envelope, the compound or the substance is heated independently of the envelope, such for example as by means of a 60 heating coil through which an electric current may be passed, or by heat arising from the heat treatment of an electrode, but most conveniently by high frequency induction in which case the material to be heated may receive heat from an electrically conducting auxiliary container therefor, or it may be directly heated by high frequency induction. By this method the substance will not become oxidized and since the main glass 65 envelope is not itself directly heated any glass which is suitable for containing caesium at normal temperatures may be employed for the main envelope. The auxiliary container for the substances may be permanently located in the main bulb itself or within an extension of the main bulb which can be subsequently sealed off from the latter and removed.

In carrying out the invention according to 80 the preferred method the main envelope of the tube consists of ordinary glass and contains for example two or more electrodes supported from the pinch of the tube and consisting for instance of a tungsten cathode, an 85 anode and a grid with appropriate lead-in conductors. The envelope is evacuated in the usual way through a tubulation and the auxiliary container such as a nickel bucket for the reagents which comprise a mixture of 90

- caesium chloride and calcium is located in an auxiliary bulb or chamber connected with the main envelope by means of a smaller tubulation and also consisting of ordinary glass.
- 5 After the usual evacuation and the removal of occluded gases from the envelope and electrodes, and while the envelope is still connected with the exhausting pump the metal bucket is heated by high frequency induction so that reaction ensues and the resulting caesium is distilled into the main envelope, the walls of which are comparatively cool so that the caesium will condense on to the inner surface thereof without condensing in any appreciable quantity upon the surface of the auxiliary bulb the walls of which are already warm by reason of the heat induced in the metal bucket by high frequency currents. Hence the caesium does not
- 10 attack the glass to an undesirable extent. When sufficient caesium has been distilled into the main envelope the auxiliary bulb is sealed off at the aforementioned tubulation.
- In a modification of the above method the
- 15 auxiliary bulb may be dispensed with and the metal bucket disposed within the main envelope itself, for example by mounting it upon one of the supporting members of the electrodes or upon one of the electrodes of the
- 20 vacuum electric tube device, in which case the bucket may be heated by high frequency currents or otherwise, and is not removed from the main envelope after the caesium has been formed.
- 25 In a further modification the caesium may be sealed into a glass capsule which is placed within the main envelope or an extension thereof and heated. The capsule is preferably disposed in a metal container and heated by high frequency induction or otherwise. Such heating causes the caesium to volatilize and to penetrate the glass capsule and thus to escape into the main envelope, the glass capsule being retained within the latter or removed with the extension. The glass capsule should be formed of a glass such as boro-silicate glass which does not easily react with caesium.
- To enable the invention to be clearly understood and carried into effect, it will now be described with reference to the accompanying drawings in which Figs. 1, 2 and 3 inclusive are elevations of vacuum electric tube devices, illustrating different methods of introducing the caesium or other vaporizable substance in accordance with the invention. Fig. 4 is a perspective view to a larger scale of an electrode similar to the electrodes shown in the preceding figures and illustrating another method of introducing the caesium or other substance. Fig. 5 is a sectional view on a larger scale of a detail, and Fig. 6 is a view illustrating a method of producing sealed capsules containing caesium or other

substances which is to be introduced into a vacuum electric tube device.

Referring first to Fig. 1 of the drawings, a three-electrode valve is illustrated comprising a tubular anode 1, within which is arranged a grid, only the support 2 of which is visible, and a filament the supports 3 and 4 of which are shown. The several electrode supports are secured in a pinch 5 formed on a flange tube 6 which is fused in the well-known manner to the glass envelope 7. A tube 8 is fused into the pinch 5 in connection with a blow hole 9 therein. The envelope 1 is adapted to be evacuated through the tube 8 which is connected to the pump manifold. The opposite end of the envelope 7 is provided with a tubular extension 10 sealed at its free end 11 and provided with a restriction at 12 so that it may be readily sealed off and removed from the main envelope 7. The sealed end 11 is in the form of a pinch in which is secured a wire 13 to which is attached a nickel tube 14 having its ends closed by pinching or otherwise and containing a quantity of a mixture of caesium chloride and calcium. The nickel tube 10 is preferably seamless or if seamed its adjacent edges should be welded together so that high frequency currents may circulate around it when induced therein.

The vacuum tube as constituted is exhausted in the usual way, the envelope being ovened for about 10 to 12 minutes at 400°, for example, after which the electrodes may be heated by high frequency induction to red heat. The filament may be heated by the passage of a current through it. After the absorbed gases have been removed upon heat treatment the nickel tube 14 may be heat treated by inducing high frequency currents therein until it becomes, for example, red hot, whereupon the reaction between the caesium chloride and the calcium takes place to produce caesium metal and calcium chloride. The metallic caesium distills into the main envelope 7 and condenses on the inner surface thereof and on the surfaces of the electrodes. Little or no caesium will condense upon the inner surface of the extension 10 since the latter will be warm by radiation of heat from the nickel tube 14, or in any case the extension 10 may be warmed by means of the sealing off torch or otherwise and the caesium thus driven into the main envelope.

When the caesium has been driven into the main bulb 7 the extension 10 may be sealed off at the constriction 12, after which the main bulb may be sealed off from the pump.

It will be understood that the process above described may be modified in various ways, for example, the caesium may be distilled into the main bulb 7 after the latter has been evacuated and disconnected from the pump. Or the heat treatment of the electrodes and the heating of the tube 14 may be effected after the valve has been evacuated

by the pumps and disconnected therefrom.

Referring to Fig. 2 the nickel tube 14 instead of being arranged in an extension of the main envelope 7 is attached to one of the 5 electrode supports, namely the support 3 for the upper end of the filament, the envelope being evacuated through the tubulation 15 at the upper end of the main bulb, instead of through a tube connected with the pinch 5.

10 The nickel tube 14 may be welded to the filament support 3 or clipped thereto. After the exhaustion and heat treatment of the bulb, the anode and nickel tube 14 may be heat treated, either before or after sealing off 15 the bulb from the pump manifold.

The nickel tube 14 may be connected by welding or otherwise to the anode, in which case the heat generated in the anode will result in the tube 14 being heated sufficiently to 20 effect the necessary chemical reaction.

Fig. 3 illustrates a modification of the process in which a piece of magnesium or calcium indicated at 16 is welded or otherwise attached to the anode 1. The magnesium or calcium 16 is then coated with caesium chloride. This may be effected in 25 the case of magnesium by mixing caesium chloride into a paste with water and then painting it on to the magnesium. When calcium is employed a non-aqueous solvent, such as ether, may be employed. When the anode is heat-treated the magnesium or calcium will reduce the caesium chloride so that 30 caesium will be vaporized into the envelope 35 7.

Instead of securing a piece of magnesium or calcium to the anode as described in connection with Fig. 3 a nickel pocket 17 may be welded to the anode as shown in Fig. 4, 40 for the reception of a mixture of caesium chloride and calcium.

In all cases wherein the reagents are secured to or supported upon the anode or are heated by heat generated in the anode, the 45 necessary heat may be alternatively effected by bombardment of electrons from the filament. In cases where the inter-electrode gap is short or where surface area of the anode is relatively small compared to that of the 50 filament, the anode may be heated to a sufficient temperature merely by radiation of heat from the filament which, in the case of tungsten, may be heated to a temperature of say 2500° K.

55 When the reagents are heated within the main bulb and a moderately volatile reducing agent such as magnesium or calcium is employed it will be appreciated that these 60 reducing agents may also be present in the bulb and serve as getters for the removal of residual gases.

Instead of introducing the caesium into the bulb in the form of a reducible compound 65 as described in connection with Figs. 1 to 4

inclusive, it may, as previously herein set forth, be introduced in the metallic state in a sealed capsule or container 18 (Fig. 5) which may be disposed in the metal tube or bucket 14 (Fig. 1). The sealed container or 70 capsule 18 conveniently consists of boro-silicate glass.

In carrying out this modification of the process the envelope 7 is connected to the pump manifold by the tube 8 and exhausted 75 while the bulb is ovened, the electrodes being next heat treated by a high frequency induction, after which the metal tube or bucket 14 is heated by high frequency induction, which causes the pressure of the metallic caesium in the capsule 18 to rise and at the same time weakens the walls of the capsule until eventually the caesium perforates the capsule and passes into the main bulb, after which the extension 10 may be sealed off at the restriction 12. Alternatively the electrodes may be 80 heat treated after the main bulb is sealed off from the pump manifold, as also may the metal tube or bucket 14. In this case the extension 10 may be removed from the bulb 90 after the latter has been sealed off from the pumps and after the caesium has been driven into the main envelope.

In some cases the metallic caesium in the capsule 18 may be heated directly by high frequency induction, in which case the nickel tube 14 can be dispensed with. The capsule can be located at other places in the envelope and heated in other ways.

Capsules such as 18 containing metallic caesium may be prepared in the following manner, reference now being made to Fig. 6. A long thin tube 20 of boro-silicate glass is provided at one end with a bulb 21 containing a mixture of caesium chloride and calcium, the other end 22 of the tube 20 being connected with a vacuum pump (not shown), the tube being preferably heat treated for the removal of occluded gases. The reagents in the bulb 21 are then heated so that they react with one another, caesium being produced and distilled into the tube 20, wherein it condenses. The bulb 21 is then sealed off from the tube 20 at 23. A portion of the tube 20 is then sealed off at 24, another portion at 25 and so on, each portion thus sealed off containing a little caesium, these sealed-off portions or capsules being adapted to be inserted in the metal tube or bucket 14 for the purpose of introducing vaporized caesium into vacuum electric tube devices in the manner already described.

It will be understood that various detail modifications may be made without departing from the scope of the invention, and that while the invention has been described primarily for the introduction of caesium into vacuum electric tube devices for increasing the electron emission of cathodes, it can be 130

applied for other purposes, such as for the introduction of volatile getters.

I claim as my invention:

The method of introducing caesium into a vacuum tube of glass susceptible to attack by caesium when hot which comprises introducing calcium and chloride of caesium (in a metallic container) into the unexhausted tube, in proximity to an electrode, exhausting 10 the tube and then heating the electrodes of the tube and thereby heating said chloride.

In testimony whereof, I have hereunto subscribed my name this third day of December, 1925.

15 ERNEST YEOMAN ROBINSON.
